(57) **CLAIM**

The ornamental design for a front face of a vehicle wheel,
as shown and described.

DESCRIPTION

FIG. 1 is a front view of a front face of a vehicle wheel
according to my novel design; and,

FIG. 2 is a perspective view from the front side of the front
face of a vehicle wheel according to my novel design.
The dash lines included depict environment and are not part
of the claimed design.

1 Claim, 2 Drawing Sheets

FIG. 1

FIG. 2
